UNITED STATES PATENT OFFICE.

ALVAN HOVEY BIXBY, OF HYDE PARK, MASSACHUSETTS, ASSIGNOR TO PEABODY ENGINEERING CORPORATION, OF NEW YORK, N. Y., A CORPORATION OF NEW YORK.

AIR REGISTER.

Application filed January 13, 1923. Serial No. 612,367.

This invention relates to air registers for admitting and controlling the delivery of air around a conical spray of liquid or finely divided fuel and more particularly for use with atomizers which have a wide range in capacity and has for its object the production of an air register of simple and cheap construction that will admit air to a boiler with the least possible confusion so that an intimate mixture of air and oil will be maintained.

A further object is to provide a register that will hold the flame to the burner and prevent pulsations common to oil burning furnaces.

The foregoing and other features of my invention will now be described in connection with the accompanying drawings forming part of this specification in which I have represented my air register in one of its applications after which I shall point out in the claims those features which I believe to be new and of my own invention.

In the drawings:

Figure 1 is a vertical cross section of my air register.

Figure 2 is a top plan view of same showing the controlling means which operates the shutter.

Figure 3 is a front view thereof.

In the carrying out of my invention the wall of any boiler, furnace or combustion chamber is shown at 1 with an opening 2. In the opening 2 I provide an annular ring 3 provided with extensions 4 having a projecting guideway 5 on the inner sides thereof.

Coaxial with the annular ring 3 I provide a shutter 6 adapted to slide upon the projecting guides 5.

In suitable bearings 7 attached to the shutter 6 is mounted a shaft 8 provided on each end with mutilated gears 9 adapted to engage racks 10 on the extensions 4. A handle 11 is provided to rock the mutilated gears and move the shutter 6 to and from its seat which is the annular ring 3.

The spray nozzle 21 may be of any well known type for injecting either liquid or powdered fuel into the combustion chamber and is provided with an inlet tube 22 which is held in position by the supporting bar 23. In Figure 3 I illustrate the bar 23 attached

to the shutter 6 by the bolts 24. With this construction the burner, diffuser, and the shutter all move when the gears 9 are rocked upon the racks 10 as will be readily understood.

On the inner part of my shutter 6 I provide a cylindrical opening 31 in which my diffuser 32 is adapted to telescopically slide. This diffuser is cylindrical in shape with a restricted end 33 somewhat larger than the tube 22 of the atomizer to be used, so that a small amount of air can enter around the atomizer. This diffuser is constructed with a sharp drop at the restricted end and does not in any manner reduce gradually or resemble the conical diffusers now generally used.

Attached to the diffuser is a handle 34 which projects through the supporting bar 23, by means of which the position of the diffuser with respect to the atomizer 21 may be adjusted at will, and the air entering around the atomizer may be regulated or entirely shut off as desired.

In oil burning the general practice seems to be to use a conical diffuser but actual experience seems to prove that the best results are obtained with cylindrical diffusers as illustrated for they hold the flame to the burner because of the fact that the light fog which is on the outside of the conical spray of oil hits the sharp edge 35 and is returned into the cone of flame. This prevents pulsations which are common to all fuel burning devices.

Deflector plates 41 held together by spacers 42 and secured to the shutter 6 by the bolts 43 are used to radiate the heat from the furnace and to preheat the air entering through the register openings.

I wish it distinctly understood that my air register herein described and illustrated is in the form in which I desire to construct it and that changes or variations may be made as may be convenient or desirable without departing from the salient features of my invention and I therefore intend the following claims to cover such modifications as naturally fall within the lines of invention.

I claim:

1. An air register comprising an annular ring adapted to fit an opening in a furnace

front, outwardly extending guides carried thereby, a frusto-conical shutter slidably mounted in said guides, means for admitting air through said shutter and means for moving the shutter toward and from the furnace front opening.

2. An air register comprising an annular ring adapted to fit an opening in a furnace front, outwardly extending guides carried thereby, a frusto-conical shutter slidably mounted in said guides, means for admitting air through said shutter and a cylindrical diffuser mounted in said shutter.

3. An air register comprising an annular ring adapted to fit an opening in a furnace front, outwardly extending guides carried thereby, a frusto-conical shutter slidably mounted in said guides, an atomizer, and a cylindrical diffuser mounted in said shutter and having a reduced portion surrounding the atomizer.

4. An air register comprising an annular ring adapted to fit an opening in a furnace front, a frusto-conical shutter movably supported by said ring, an atomizer, and a cylindrical diffuser mounted in said shutter and surrounding said atomizer.

5. An air register comprising an annular ring adapted to fit an opening in a furnace front, a frusto-conical shutter movably supported by said ring, an atomizer, a cylindrical diffuser surrounding said atomizer, and a

series of deflector plates supported by said shutter.

6. An air register comprising an annular ring adapted to fit an opening in a furnace front, a frusto-conical shutter movably supported by said ring, a support carried by said shutter, an atomizer mounted in said support, and a cylindrical diffuser mounted in said shutter and having a reduced portion surrounding said atomizer.

7. An air register comprising an annular ring adapted to fit an opening in a furnace front, a frusto-conical shutter movably supported by said ring, a support carried by the shutter, an atomizer mounted in said support, a cylindrical diffuser mounted in said shutter and a series of deflector plates supported by said shutter.

8. An air register comprising an annular ring adapted to fit an opening in a furnace front, a frusto-conical shutter movably supported by said ring, an atomizer, cylindrical diffuser, and deflector plates all carried by said shutter, and means for adjusting the shutter and connected parts toward and from the said furnace front opening.

Signed at 135 Broadway, New York, in the county of New York and State of New York this eleventh day of January, A. D. 1923.

ALVAN HOVEY BIXBY.
